UNITED STATES PATENT OFFICE

97,684

DESIGN FOR AN ENSEMBLE DRESS

Emil Schwartz, New York, N. Y.

Application November 2, 1935, Serial No. 59,329

Term of patent 3½ years

To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

Figure 1 is a front view of an ensemble dress showing my new design.

Figure 2 is a rear view of the ensemble dress shown in Figure 1.

Figure 3 is a front view of the dress unit of the ensemble dress shown in Figure 1.

Figure 4 is a rear view of the dress unit of the ensemble dress shown in Figure 3.

The floral designs on the front of the collar portion of the dress, and on the front of the jacket, represent quilted embroidery.

The lines radiating from the scalloped edges of the jacket, and from the collar and sleeve portions of the dress, represent embroidery.

The lines extending down the front and back of the waist portion of the dress member, represent pleats.

I claim:

The ornamental design for an ensemble dress, substantially as shown, and described.

EMIL SCHWARTZ.
